UNITED STATES PATENT OFFICE

SIMON W. FARBER, OF BROOKLYN, NEW YORK, ASSIGNOR TO S. W. FARBER, INC., OF BROOKLYN, NEW YORK, A CORPORATION OF NEW YORK

LAMP-SHADE SUPPORT

Application filed January 17, 1929. Serial No. 333,103.

My invention relates to a new and improved lamp shade support.

One of the objects of my invention is to provide a lamp shade support which can be readily applied to a lamp shade made of fragile material, such as glass or the like.

Another object of my invention is to provide a simple and efficient device of this type, which can be readily applied and removed.

Another object of my invention is to provide a device of this type which can be held to the lamp shade by means of a series of clamping screws.

Other objects of my invention will be set forth in the following description and drawings which illustrate a preferred embodiment thereof, it being understood that the above general statement of the objects of my invention is intended merely to generally explain the same and not to limit it in any manner.

Fig. 1 is a rear elevation.

Fig. 2 is a plan view.

Fig. 3 is a sectional view on the line 3—3 of Fig. 1.

Fig. 4 is a similar sectional view, showing a different embodiment of my invention, in which the reinforcing frame is omitted.

Fig. 5 is a plan view of the inner reinforcing frame used in one of the embodiments of the invention.

The lamp shade 1 may be made of any suitable material such as glass which may be partly translucent. The outside of the shade 1 may be colored green, or any other color desired. The shade 1 is formed with a holding flange 2. This holding flange 2 has a general curved or arcuate form. The said flange 2 has a transverse section which has a double curvature as shown in Fig. 3. A reinforcing frame 3 is applied to and is frictionally held upon the holding flange 2. It will be noted that the holding flange 2 projects laterally from the shade 1.

This reinforcing frame 3 may be made of any suitable resilient metal. However, if desired it could also be made of soft material such as rubber. The purpose of this reinforcing frame 3 is to prevent the flange 2

from cracking or being distorted by the pressure of the holding screws.

The clamping frame 4 is preferably made of any suitable metal and its shape is generally similar to that of the holding flange 2. The clamping frame 4 is substantially U-shaped. The clamping flange 4 is provided with a plurality of cups, in which clamping screws 5 are located. The inner walls of these cups 12 may have internally threaded openings, which cooperate with the threaded shanks of said clamping screws 5. If desired, the adjacent openings in the clamping frame 4 could also be internally threaded, although this is not necessary. When the clamping screws 5 are turned, their inner ends are caused to bear against the reinforcing frame 3 so that the holding frame 4 is tightly clamped in position. The inner face of the holding frame 4 is provided with a bar 10 upon which a socket for the electric bulb B is mounted.

Likewise, the swivel S is provided with a coupling nipple 8 to which the standard of the lamp can be connected so that it can be placed upon a desk or the like.

In the embodiment shown in Fig. 4, the reinforcing frame 3 is omitted.

It will be noted that the underside of the reinforcing frame 3 has an inner curved portion which generally corresponds to the transverse convex contour of the flange 2. The outer end of the frame 3 makes little or no contact with the holding flange 2. The upper face of the frame 3 makes only partial contact with the adjacent upper face of the holding flange 2. The inner portion of the upper wall of the holding frame 3, which receives the thrust of the clamping screws 5, is spaced from the concave upper face of the holding flange 2. Hence substantial pressure can be applied by means of the clamping screws 5, without any danger of cracking or otherwise injuring the relatively fragile material of the lamp shade 1.

For convenience in description, it may be assumed that the shade is held with the flange 2 and the frames 3 and 4 in substantially horizontal position, as this is the normal position of the device, although the

shade 1 may of course be tilted somewhat from this position. It will be noted that the flange 2 is transversely curved, as clearly shown in Fig. 1, in addition to the general double curvature in the lateral or horizontal direction, which is clearly shown in Figs. 3 and 4. This configuration of the parts permits the shade and its reinforcing frame to be readily inserted within the clamping frame and it also enables the clamping pressure of the screws 5 to be readily applied, without any danger of cracking the shade 1, if this is made of frangible material.

It will be noted that the shade is open 15 at its bottom and that the flange 2 does not extend below its bottom so that the transverse contour line of flange 2 is an incomplete curve.

I have shown a preferred embodiment of 20 my invention, but it is clear that numerous changes and omissions can be made without departing from the spirit of my invention. For example, the cups 12 may be soldered or affixed to the clamping frame 4 in any 25 suitable manner.

I claim:

1. In combination, a lamp shade open at 30 its bottom and closed at its top and having at one side thereof a horizontally projecting and transversely curved flange whose transverse contour line is an incomplete curve, a holding frame having spaced walls between which said flange is slidably located, said holding frame being in horizontal position and having walls which are superposed when the shade is in normal operative position, said frame having a substantially U-shaped cross section conforming to the shape of said flange, said frame having holding 40 means connected thereto, said holding means being movable in a direction which is substantially perpendicular to the walls of the frame, said holding means being operable from the outside of said frame.

2. In combination, a lamp shade open at 45 its bottom and having a horizontally projecting flange which has a double curvature in the horizontal direction, said flange being transversely curved, and a frame in which 50 said flange is adapted to be removably located, the transverse contour line of said flange being an incomplete curve.

3. A lamp shade open at its bottom and 55 having a horizontally projecting flange which is laterally curved, so that said flange has a lateral concave wall portion, a reinforcing frame fitting over said flange, and having a portion extending over and spaced 60 from said lateral concave wall portion, and a clamping frame of substantially U-shaped cross-section having walls between which said flange and said reinforcing frame are adapted to be removably located, and clamping 65 means provided for said clamping frame

and adapted to bear against said spaced portion of the wall of said frame.

4. A lamp shade open at its bottom and having a horizontally projecting flange which is laterally curved, so that said flange 70 has a lateral concave wall portion, a reinforcing frame fitting over said flange, and having a portion extending over and spaced from said lateral concave wall portion, and a clamping frame of substantially U-shaped 75 cross-section having walls between which said flange and said reinforcing frame are adapted to be removably located, and clamping means provided in said clamping frame and adapted to bear against said spaced portion of the wall of said frame, said flange and said reinforcing frame and said clamping frame being transversely curved and having transverse contour lines which are 80 incomplete curves.

5. In combination, a lamp shade, a laterally projecting flange at the rear thereof, the transverse contour line of said flange being an incomplete curve, and a support having a portion thereof of corresponding arcuate 90 shape and adapted to bear against the under face of the said flange, said support having a lamp supporting arm connected thereto and extending within the said shade, and clamping means adapted to clamp the said flange to the said support.

In testimony whereof I affix my signature.
SIMON W. FARBER.
